UNITED STATES PATENT OFFICE

ARTHUR K. LAUKEL, OF DETROIT, MICHIGAN

CORE BOX

Original application filed January 13, 1927, Serial No. 160,862. Divided and this application filed May 23, 1929. Serial No. 365,343.

This application is a division of my co-pending application Serial No. 160,862, filed January 13, 1927.

This invention relates to the manufacture of metal core boxes by electro-deposition such as in the manner described in my pending application for Letters Patent of the United States, Serial No. 101,069, filed April 10, 1926, and has for its object to provide in a simple manner for the special protection of sharp edges about the cavity of the core box so as to increase their resistance wear under the abraiding influence of core sand or similar material.

Generally for the sake of cheapness and expediency in electro-deposition it is preferred to use copper as the metal of the core box, and as this metal is somewhat soft, the sharp exposed edges thereof are more or less easily burred over at the face or parting line of the box, and to resist this tendency to burr at such edges I propose to provide the core box with a face of hard metal extending to the outlines of the cavity of the box and thereby protecting the aforesaid exposed edges. It is also proposed to provide such hard metal face by means of electro-deposition in the process of manufacturing the core box, and also to effect the electro-deposition of such hard metal upon a previously deposited film of copper which is subsequently removed from the hard metal in the cleaning up of the finished core box.

The invention is fully disclosed by way of example in the following description and in the accompanying drawings in which

Figure 1 is an elevation of a mold used in the electrolytic production of a core box;

Figure 2 is a transverse section of the same; Figure 3 is a similar transverse section illustrating a mold with a face plate applied thereto and a plate of hard metal deposited on the mold at the required place;

Figure 4 is a similar view of Figure 1,

illustrating the condition of the mold according to Figure 3;

Figure 5 is a transverse section of the mold after all of the plating operations are complete;

Figure 6 is a perspective view illustrating the electro-deposited core box removed from the mold; and

Figure 7 is a fragmentary detail sectional view illustrating a modification of the process.

Reference to these views will now be made by use of like characters which are employed to designate corresponding parts throughout.

The numeral 1 indicates a mold comprising a base 2 on the face of which projects a pattern 3 for the formation of the cavity of a core box, and according to an arrangement which I have found very satisfactory, the face of the mold is recessed as at 4 for the reception of a face plate 5 of brass or similar rigid material, the inner margin 4a of the said recess 4 roughly following the outline of the projecting pattern 3.

The said mold is prepared for plating by providing a conductive surface 6 on the mold immediately surrounding the pattern 3 as indicated in Figure 2, this being preferably done before the application of the face plate 5 to the mold so that the inner margins of the face plate will overlap the said conductive surface. On this surface I then electrolytically deposit a plate of metal of a wear resisting quality comparative to the principal metal of which the electro-deposited parts of the core box are to be made. Thus, where the electro-deposited core box is to be of copper the electro-deposited plate referred to may be of nickel. This is indicated by the reference numeral 7. It will be observed that this plate of nickel of wear resisting metal extends from the inner margins of the face plate 5 to and into the angles between the pattern proper 3 of the mold and the base 2 thereof.

Following this, the pattern proper 3 is

provided with a conducting surface and the copper or softer metal 8 then deposited over the said pattern 3 and over the hard metal plate 7, said copper extending to and over the preferably beveled inner margins of the face plate 5. During the plating operations referred to the exposed surface of the face plate may be protected from unnecessary deposited metal thereon by a suitable insulator 9.

10 After these operations have taken place the resulting shell upon removal will have the appearance indicated in Figure 6 wherein it will be seen that extending between the face place 5 and the edges of the cavity of the core box is the marginal film of hard metal so that the sharp edges are of a wear resisting nature and much less likely to be damaged or burred by the action of core sand being 15 rammed into the core box.

20 According to Figure 7 the depositing of the wear resisting metal is first proceeded by a flashing 10 of copper or other metal adapted to form a specially suitable surface for the 25 depositing of such wear resisting metal, for instance, where the conducting surface of the mold is of silver sulphide, there may ordinarily be a tendency of nickel to become detached therefrom or peal, and to prevent this an 30 initial flashing of copper is deposited on the sulphide surface, to which flashing the nickel will adhere much more closely. The flashing may be readily removed if necessary or desirable from the surface of nickel after the 35 removal of the shell from the mold.

40 A longer wearing core box may be secured in the manner described, with little difficulty, and the said invention overcomes one of the objections sometimes met with in the use of 45 electro-deposited copper core boxes where they are utilized in high production work and subjected to abuse in the making of cores therefrom.

50 Although specific embodiments of the invention have been illustrated and described, it will be understood that various alterations in the details of construction may be made without departing from the scope of the invention as indicated by the appended claims.

55 What I claim is:

1. In a metal core box having a molding face defining a cavity, a face plate surrounding said cavity, a wear piece of a relatively hard metal embedded in said face plate at the 60 margin of said cavity and extending to the wall of said cavity, the remainder of said molding face being of a less hard metal.

65 2. In a metal core box having a molding face defining a cavity, a face plate surrounding said cavity, a wear piece of a relatively hard metal embedded in said face plate at the margin of said cavity and extending to the wall of said cavity, the remainder of 70 said molding face being of a less hard metal,

the face and wear piece being bonded together at all points of contact.

75 3. In a metal core box having a molding face defining a cavity, a face plate surrounding said cavity, a wear piece of a relatively hard metal embedded in said face plate at the margin of said cavity and extending to the wall of said cavity, the remainder of said molding face being of a less hard metal, the face and wear piece being electrolytically 80 bonded together at all points of contact.

85 In witness whereof I have hereunto set my hand.

ARTHUR K. LAUKEL.
